(57) **CLAIM**

The ornamental design for a clamp assembly, as shown and described.

DESCRIPTION

FIG. 1 is a front, top, right side isometric view of a clamp assembly in accordance with our design;

FIG. 2 is a front elevation view thereof;

FIG. 3 is a rear elevation view thereof;

FIG. 4 is a top plan elevation view thereof;

FIG. 5 is a bottom plan view thereof;

FIG. 6 is a right side elevation view thereof; and,

FIG. 7 is a left side elevation view thereof.

The broken lines depict portions of the article that form no part of the claimed design.
